ABSTRACT

A grain drying and storage bin comprising structural elements providing a floor and ceiling and walls extending generally vertically therebetween to define a space for receiving grain, and at least one divider disposed in the space to extend vertically therein from a point adjacent the floor to a point adjacent the ceiling to divide the space into a plurality of generally vertically extending grain cells, each grain cell having a limited lateral width. Each divider extends across the grain receiving space to provide opposite vertically extending side edge or end edge portions adjacent, respectively, opposite sides or ends of the bin. Each divider is defined by a pair of vertically extending side walls spaced apart to provide a vertical air space therebetween extending transversely across the grain receiving space between adjacent grain cells. The side walls of the divider are formed primarily by a mesh material through which the air circulates to dry the grain in the cells.

10 Claims, 3 Drawing Figures

GRAIN BIN

The present invention relates to grain drying and storage bins, and more particularly to the provision of such a bin constructed to provide for natural drying of the grain which may be picked, for instance, at inordinately high moisture levels.

Generally, presently, grain such as corn is picked at inordinately high moisture levels and then forcibly dried by very expensive techniques involving the use of natural gas or liquid propane gas burners and forced movement of the drastically heated air through the grain. Not only is the energy usage expensive and time-consuming, a considerable amount of the feed value of the grain is lost because of the deleterious effect of the heated air upon the grain.

On the other hand, if wet grain or grain having a high moisture content is merely dumped into a conventional storage bin, the grain will very often spoil.

It is my invention, therefore, to provide a grain drying and storage bin constructed such that air is circulated naturally through the grain to dry the grain over a period of time and to prevent spoilage of the grain. Particularly, it is my concept to provide a grain drying and storage bin which comprises, within the space defined by the bin, a plurality of dividers which serve to divide the space into a plurality of generally vertically extending grain cells, each cell having a limited lateral width such as, for instance, 18 inches. Each divider is constructed to provide an air passageway through the bin, for instance, 6 inches wide and extending from a point adjacent the floor to a point adjacent the ceiling. The grain is held out of these passageways by a screen wire mesh which may be, for instance, a 3/16 inch wire mesh.

The ends of the dividers or the ends of the air passageways therethrough are open to the atmosphere outside the bin, and the bin may be placed such that the open ends of the passageways face the normal wind direction. This provides for natural air movement through the divider air passageways.

Other objects and features of the present invention will become apparent as this description progresses.

To the accomplishment of the above and related objects, this invention may be embodied in the form illustrated in the accompanying drawings, attention being called to the fact, however, that the drawings are illustrative only, and that changes may be made in the specific construction illustrated and described, so long as the scope of the appended claims is not violated.

In the drawings:

FIG. 1 is a perspective view, partially cut away, of two grain drying and storage bins in accordance with the present invention connected together under one roof structure;

FIG. 2 is a sectional view taken generally along the line 2-2 in FIG. 1 and reduced in scale; and

FIG. 3 is a fragmentary perspective view of a divider in the bin.

Referring now particularly to the drawings, the bin is indicated generally at 10 and includes two separate bins 12, 14 constructed in accordance with the present invention and connected together. Any number of such bins 12, 14 can be connected together under a common roof structure as desired. The bin 10 rests upon concrete footings 16, 18, 20 which may be poured in strips running from the front of the bin to the rear of the bin as illustrated. Structural members, such as heavy steel

angle irons 22, may rest upon and extend longitudinally along the footings while other such structural members 24 may extend between the footings as illustrated to provide means for fastening the framework of the bin to the footings. Each illustrative bin 12, 14, which may be identical, includes four corner posts 30, 32, 34, 36 extending vertically upwardly to be connected together at their upper ends by cross braces 38, 40 and at their lower ends by floor joists 42, 44, 46, 48. A plurality of support posts 52, as needed, support the floor joists upon the footings.

The floor of each bin includes a left-hand portion 56 sloping toward the center and a similar right-hand portion 58 sloping toward the center. I place an unloading auger 60 in the center of the floor to extend from the front side of the bin to the rear side of the bin to unload the grain therefrom as indicated by the arrow 62 in FIG. 2. A plurality of studs 68, as needed, extend between the floor joists and the upper braces to provide structural strength and to support a roof structure indicated generally at 70 comprising rafters 72 and roof panels 74. The eaves of the roof structure may preferably be defined primarily by a wire screen mesh material 76 which provides for air circulation.

The structural means discussed thus far is merely illustrative, and it will be appreciated that bins in accordance with the present invention may be constructed using many different types of structural elements connected together in many different ways.

Therefore, my invention is a grain drying and storage bin comprising structural means providing a floor and ceiling and wall means extending generally vertically therebetween to define a space for receiving grain, with at least one divider disposed in the space to extend vertically therein from a point adjacent the floor to a point adjacent the ceiling to divide the space into a plurality of generally vertically extending grain cells. Each divider extends across the space of the grain bin to provide opposite, vertically extending side edge portions adjacent, respectively, opposite sides or ends of the bin. Each divider is defined by a pair of vertically extending side walls spaced apart to provide a vertical air space therebetween extending across the grain receiving space between adjacent grain cells, the side walls being formed primarily by a mesh material through which air circulates to dry the grain in the cells.

In the illustrative embodiment, each bin 12, 14, includes three such dividers 80, 82, 84. Assume that the left-hand end in FIG. 2 is the front end of the bin while the right-hand end is the rear end. The illustrative dividers 80, 82, 84 extend from the front end to the rear end of the bin or transversely across or through the grain receiving space of the bin to divide the bin into grain cells 86, 88, 90, 92.

Each illustrative divider (FIG. 3) may preferably be constructed by welding or otherwise securely fastening together a plurality of steel rods 100 to provide a rectangularly shaped hollow framework covered by a screen mesh material which may be welded or otherwise securely fastened to the framework. Each divider, therefore, has parallel, spaced apart side walls defined primarily by the screen mesh material with a sufficient space between the side walls indicated at 112, 114 (FIG. 2) to provide for air circulation through the dividers and consequently through the bin.

The dividers 80, 84 may be supported a few inches above the floor portions 56, 58 by legs indicated at 120

so that the grain can flow thereunder while the divider 82 may be supported above the auger 60 to permit operation of the auger.

The side edges or end edges of the dividers indicated at 80a, 82a, 84a may lie in the same general plane as the front and rear wall means of the bin 12, and the front and rear wall means may comprise vertically extending perforated panels 130, the panels terminating, respectively, at the side walls 112, 114 of the dividers such that the divider air spaces are open to the atmosphere outside the bin. The front and rear walls of the bins 12, 14 may include vertically extending studs (not shown) adjacent each divider side wall and to which the panels 130 are fastened. Similar panels 132 may extend between the studs 68 on the side walls of the bins. The panels are perforated to permit some air circulation therethrough. The primary means of circulating air through the bin and through the grain stored in the bin is through the dividers 80, 82, 84. Assume that the bin 10 is located on the farm such that the right-hand end as viewed in FIG. 2 is facing the normal wind direction. The wind forces air into the end of the dividers as indicated by the arrows 136 to flow through the dividers and through the side walls of the dividers as indicated by the arrows 138 to dry the grain in the cells 86, 88, 90, 92. This air movement coupled with the laterally narrow grain cells will dry the grain and prevent any damage resulting from inordinately wet grain being placed in the cells.

For illustrative purposes, I shall now provide overall dimensions of the bin 12 to establish the manner in which the grain drying will occur. The height of the bin, of course, may be optional to provide economy of construction. For instance, a height of 20 feet would be reasonable and a depth or distance from the front wall to the rear wall of 20 feet would be satisfactory. Each grain cell may be only 1-1/2 feet wide, i.e., the distance between the dividers may be only 1-1/2 feet. The distance between the side walls of each divider may be, for instance, 6 inches. Thus, the overall width of the bin 12 may be approximately 7-1/2 feet. Each divider 80, 82, 84 may be provided in four sections 20 feet tall and 5 feet wide constructed in the factory and then connected together within the bin 12. Each divider may be covered with a 3/16 inch screen wire mesh.

Thus, at no point in the bin 12 will any kernel of grain be more than 18 inches from an air passageway, and most of the grain, particularly the grain between the dividers 80, 82 and the dividers 82, 84 will be less than 9 inches away from an air passageway. While the drying may occur at a much slower rate than the forced drying practices presently being used, the grain will not spoil because of the close proximity of the air passageways to the grain.

In this application and its claims, the term "grain" is intended to refer to shelled corn or any other small grain or legumes such as soybeans.

It will further be appreciated that the perforated panels 130, 132 may be replaced by wire mesh screens to provide even more air circulation.

I claim:

1. A grain drying a storage bin comprising structural means providing a sloping floor having a low point to which the grain flows by gravity and a ceiling and wall means extending generally vertically therebetween to define a space for receiving grain, and at least one divider disposed in said space to extend vertically therein

from a point adjacent and spaced upwardly from said floor to a point adjacent said ceiling to divide said space into a plurality of generally vertically extending grain cells; said upward spacing of said divider allowing removal of grain from said bin at said low point on said sloping floor, each divider extending across said space to provide opposite vertically extending side edge portions adjacent, respectively, opposite sides of said bin, each divider being defined by a pair of vertically extending side walls spaced apart to provide a vertical air space therebetween extending transversely across said grain receiving space between adjacent grain cells, and said side walls being formed primarily by a mesh material through which the air circulates to dry the grain in said cells.

2. The invention of claim 1 in which each said divider includes a plurality of rods rigidly connected together providing a framework having said side walls, said framework side walls being covered with said mesh material.

3. The invention of claim 1 in which each said grain cell has opposite ends adjacent, respectively, said opposite sides of said bin and said wall means of said bin includes vertically extending panel means covering the ends of said grain cells, said panel means terminating, respectively, at the side walls of the said side edge portions of said dividers such that said divider air spaces are open to the atmosphere outside said bin.

4. The invention of claim 3 in which said panel means are perforated sheets of material through which air circulates.

5. The invention of claim 4 in which each said divider includes a plurality of rods rigidly connected together providing a framework having said side walls, said framework side walls being covered with said mesh material.

6. The invention of claim 3 in which each said divider includes a plurality of rods rigidly connected together providing a framework having said side walls, said framework side walls being covered with said mesh material.

7. A grain drying and storage bin comprising structural means providing a floor having a low point, a ceiling, front wall means, rear wall means, and side wall means defining a space for receiving grain, and a plurality of dividers disposed in said space to extend vertically therein from a point adjacent said floor to a point adjacent said ceiling to divide said space into a plurality of generally vertically extending grain cells, each divider extending across said space from said front wall means to said rear wall means, each divider being defined by a pair of vertically extending side walls spaced apart to provide a vertical air space therebetween extending from the front to the rear of said space between adjacent grain cells, said floor sloping toward said low point to cause the grain to flow for unloading purposes, said dividers being supported on legs above said floor to permit the grain to flow thereunder, and said side walls being formed primarily by a mesh material through which the air circulates to dry the grain in said cells.

8. The invention of claim 7 in which each said divider includes a plurality of rods rigidly connected together providing a framework having said side walls, said framework side walls being covered with said mesh material.

9. The invention of claim 7 in which said front and rear wall means include vertically extending panel means covering the front ends and rear ends of said grain cells, said panel means terminating, respectively, at the side walls of said dividers such that said divider

air spaces are open to the atmosphere outside said bin.

10. The invention of claim 8 in which said dividers include divider sections fastened together in said bin to provide said divider air spaces.
